RIVETING MACHINE

Frank H. Le Jeune, Jackson, Mich., assignor to
Kelsey-Hayes Wheel Company, Detroit, Mich.,
a corporation of Delaware

Application December 27, 1948, Serial No. 67,302

11 Claims. (Cl. 218—0.5)

1

The invention relates to riveting machines and refers more particularly to machines for riveting linings to brake shoes.

The invention has for one of its objects to provide an improved construction of automatic riveting machine which accurately accomplishes the riveting at a fast rate.

The invention has for another object to provide a machine for riveting two work elements by a plurality of series of rivets, the machine having independently operable riveter heads which are controlled independently of each other so that the spacing of the rivets in one series may be different than that of the rivets in another series.

The invention has for further objects to provide a riveting machine having a rotatable work holder carrying peripheral anvils and also having a reciprocable plunger movable substantially radially of the holder for cooperating with the anvils to effect the riveting; to provide a riveting machine in which the work holder carries means for controlling the operation of the plunger; to provide a riveting machine having means for automatically pressing one element of the work against the other element of the work during the riveting operation; to provide the riveting machine with means for properly positioning both of the work elements relative to the holder; and to provide the riveting machine with means for properly positioning the work elements relative to each other.

With these as well as other objects in view the invention resides in the novel features of construction and combinations and arrangements of parts as more fully hereinafter set forth:

In the drawings:

Figure 1 is a front elevation of the riveting machine;

Figure 2 is an enlarged view of a portion thereof;

Figure 3 is a cross section on the line 3—3 of Figure 2;

Figure 4 is a cross section on the line 4—4 of Figure 3;

Figure 5 is a cross section on the line 5—5 of Figure 4;

Figure 6 is a cross section on the line 6—6 of Figure 4;

Figure 7 is a cross section on the line 7—7 of Figure 6;

Figures 8 and 9 are cross sections on the line 8—8 and 9—9 respectively of Figure 5;

Figure 10 is a cross section on the line 10—10 of Figure 4;

Figure 11 is an enlarged sectional view of a portion of the riveting mechanism;

2

Figure 12 is an elevation of a portion of the work holder;

Figure 13 is a cross section taken on the line 13—13 of Figure 3; and

Figure 14 is a cross section on the line 14—14 of Figure 4.

As illustrated in the present instance, the rivet machine is designed to rivet linings to brake shoes, the latter being webbed and more particularly of T-cross section.

The riveting machine has the pair of independent like riveter heads 1, the construction of each riveter head being conventional and its operation being well known to those skilled in the art. Generally, each riveter head comprises the frame 2, the rivet hopper 3, the rivet carrier 4 to which the rivets are successively conducted by a chute leading from the hopper, the vertically reciprocable rivet carrier slide 5, the vertically reciprocable rivet driver 6 which is in the nature of a plunger and the vertically reciprocable rivet driver slide 7. The rivet driver slide 7 is connected to the crank 8 of the crank shaft 9 which is journalled in the frame 2. The crank shaft has journalled on its end the fly wheel 10 which is adapted to be operatively connected to the crank shaft by the conventional clutch 11. The fly wheel is also adapted to be driven by suitable means such as the electric motor 12 operatively connected to the fly wheel by a belt.

The riveting machine also has the work holder 13 which is provided with the channel 14 for receiving the webs 15 of a pair of angularly spaced peripheral brake shoes 16 and linings 17, each shoe having predeterminedly located radial holes in its platform 18 and each lining having corresponding holes registering with the holes in the platform. The holes in the platform are arranged in laterally or axially spaced series at opposite sides of the web with the holes of each series arranged in a row and circumferentially spaced from each other. In the instance, the circumferential spacing of the holes of one series is different from that of the holes of the other series (Fig. 12), the holes of both series at each end of the platform being aligned laterally or axially of the platform and the intermediate holes of each series being staggered relative to the other.

The work holder is preferably made of the two circular disks 19 and 20 fixedly secured together by suitable means such as head screws and cooperating to form the channel 14, the disks being journalled on the horizontal shaft 21 which extends between and is mounted in the frame plates 22 and 23. These frame plates rest on and are

fixedly secured to the base 24 which in turn is supported on and fixedly secured to the table 25. Each of the disks carries two angularly spaced series of circumferentially spaced anvils extending radially beyond the disk and adapted to engage the radially inner sides of the platforms of the shoes. The anvils of both series are arranged in rows and register with the holes in the shoe platforms and have their radially outer end portions shaped to form heads on the inner ends of the shanks of the rivets at the radially inner sides of the platforms. The rivets are of conventional construction with their inner ends, which are to be turned over and formed into heads, made hollow. More particularly each series of anvils comprises the leading anvil 26 and the succeeding anvils 27. Each leading anvil 26 is formed with the body 28 extending radially of the disk and with the axial pin 29 which is resiliently urged radially outwardly of the disk by the coil spring 30 to normally extend through the holes in the leading ends of the brake shoe platform 18 and lining 17. The pin is movable downwardly by the rivet as the latter is forced downwardly by the rivet driver or plunger of the riveter head and finally comes to rest in a position to cooperate with the body of the leading anvil to effect the heading of the lower end of the shank of a leading rivet. More particularly the upper end of the pin is tapered and the upper end of the body of the leading anvil has a conical cavity into which the tapered upper end of the pin extends when the pin is in its lowermost position. As a result the pin spreads out the lower end of the shank of the rivet into the cavity. Each succeeding anvil 27 is formed with the solid body 31 having at its upper end a cavity like that formed by the body of the leading anvil and the pin in its lowermost position. With this construction the leading anvils of the series of anvils of both disks cooperate to effectively angularly position the shoes and linings about the periphery of the work holder.

Each riveter head 1 is mounted on the column 32 of the riveting machine beyond the ends of the table 25 and to accurately position the riveter heads so that their rivet drivers or plungers 6 are in the planes of the axes of the anvils 26 and 27 carried by the holders, there is the block 33 secured to each column 32 and the bolt 34 non-rotatably secured to the base of the frame 2 of each riveter head 1 and slidably engaging the upper end of the block and threadedly engaged by the nuts 35 which are adapted to abut the opposite sides of the block. With this construction the riveter heads may be adjusted toward and away from each other to locate the rivet drivers or plungers with their axes in the planes of the axes of the rows of anvils.

To index the holder 13 so that the anvils are successively axially aligned or registered with their respective rivet drivers or plungers, means is provided for angularly advancing the holder about its axis step by step and for also holding the holder in each position of angular adjustment. In detail, 36 is an indexing plate concentric with and fixedly secured to the disk 19 and having the concentric inner series of angularly spaced fixed abutment pins 37 secured thereto and extending laterally therebeyond and the concentric outer series of angularly spaced holes 38 extending transversely therethrough. The pins and holes are arranged in pairs with the axes of the pin and hole of each pair in a radial plane and the hole radially outwardly of the pin. Cer-

tain of the pairs of pins and holes are located diametrically opposite the anvils, other pairs of pins and holes being diametrically opposite the gaps between the series of anvils for use in indexing the holder.

39 is a horizontally reciprocable slide movable chordwise of the holder and guided by the upper and lower gibs 40 and 41 (Figs. 5, 8 and 9) which are fixedly secured to the frame plate 22. 42 is a dog pivotally connected at one end by the vertical pivot pin 43 to the slide and urged laterally toward the indexing plate 36 by means of the coil spring 44 carried by the slide, the frame plate 22 being formed with the horizontal elongated opening 45 through which the dog extends. The free end of the dog has the abutment face 46 for successively engaging the abutment pins 37 during the forward strokes of the slide 39 and thereby angularly rotating the holder step by step, the forward movement of the slide stopping when the particular abutment pin engaged by the abutment face is in its lowermost position and diametrically opposite a rivet driver or plunger 6 of a riveter head so that the uppermost anvil extends vertically in axial alignment or registration with a rivet driver or plunger. The vertical height of the abutment face 46, it will be noted, is such that the abutment face is engageable with the abutment pin next in rear of the lowermost abutment pin so that during the forward stroke of the slide the next in rear abutment pin moves downwardly along the abutment face of the dog. To provide for the dog moving over the next in rear pin during the rearward stroke of the slide, 35 the dog has the cam 47 near its free end and on its side facing the abutment pins, the cam being adapted to ride over the next in rear pin and thereby swing the dog about its vertical pivot pin laterally against the resistance of the coil spring 44.

For frictionally resisting rotation of the work holder there is the spring pressed shoe 5 mounted on the frame plate 23 and slidably engaging the outer side of the disk 20.

48 (Fig. 4) is a positioning pin carried by the frame plate 22 and engageable successively in the holes 38 when in their lowermost position. The positioning pin is slidable in the flanged bushing 49 which extends through the frame plate 22 and is threaded into the cup-shaped nut 50 at the same side of the frame plate as the slide 39. The positioning pin has the reduced shank 51 which extends through the bottom of the nut and has secured to its end the pull out collar 52. 53 is a coil spring within the nut and encircling the reduced shank and abutting the bottom of the nut and the enlarged portion of the pin for yieldably urging the pin in a direction to extend into a hole 38 when in registration with the pin.

60 For horizontally reciprocating the slide 39, there is the actuator plate 54 fixedly secured to the slide 39 and carrying the roll 55. There is also the cam wheel 56 journalled on the shaft 21 and having the cam groove 57 (Figs. 3, 4 and 8) receiving the roll 55. The cam wheel is driven continuously during the setting of the rivets in one brake band by the electric motor 58 by means of the sheave 59 and the belt 60, the sheave being at one side of and keyed to the cam wheel 56.

70 For the purpose of withdrawing the positioning pin 48 from the lowermost hole 38, there is the cam 61 located between the slide 39 and the actuator plate 54 and secured to the actuator plate by suitable means such as the dowel pins 62. This cam has the furcations 63 between which a boss

on the collar 52 extends. These furcations extend between the nut 50 and pull out collar 52 and have the cam faces 64 engageable with the pull out collar upon the rearward stroke of the slide to disengage the positioning pin 48 from its registering hole and hold this pin away from the indexing plate 36 until the latter has been advanced by the slide during the next forward stroke of the slide a sufficient distance such that the positioning pin cannot re-engage the hole.

For the purpose of actuating a clutch for moving the rivet driver or plunger of each riveter head downwardly, I have provided a solenoid 65 for each riveter head and a means for controlling the energization of each solenoid. Each solenoid is operatively connected to the clutch 11 of the respective riveter head to connect the associated crank shaft 9 and fly wheel 10 when the electric circuit including the solenoid is made. The means for making and breaking the electric circuit of the solenoid 65 at the lefthand side of the riveting machine comprises the solenoid controlling time limit switch 66 and the two inner series of angularly spaced control pins 66¹, 66² and 66³ for operating said limit switch, these control pins being concentrically mounted on and projecting laterally beyond the face of the ring 67 which is concentrically fixedly secured to the disk 19. The means for making and breaking the electric circuit of the solenoid at the righthand side of the riveting machine comprises the solenoid controlling time limit switch 68 and the two outer series of angularly spaced control pins 68¹, 68², 68³ and 68⁴ for operating said limit switch, these control pins also being concentrically mounted on and projecting laterally beyond the face of the ring 67. The limit switches 66 and 68 are mounted on the frame plate 22 and are conventional limit switches of standard construction. Each limit switch is provided with the pivotal arm 69 having at its free end portion the abutment pin 69' which is movable by a control pin engageable with the abutment pin. The control pins 66¹, 66² and 66³ are positioned to operate the limit switch 66 and successively make the electric circuit to the solenoid 65 of the lefthand side riveter head when the registering holes of the lefthand row in the lining 17 and platform 18 are successively brought into registration with the rivet driver or plunger of the lefthand riveter head. The control pins 68¹, 68², 68³, and 68⁴ are positioned to operate the limit switch 68 and successively make the electric circuit to the solenoid 65 of the righthand side riveter head when the registering holes of the righthand row in the lining 17 and platform 18 are successively brought into registration with the rivet driver or plunger of the righthand riveter head.

The timing of the indexing of the holder 13 is such that the holder is held from rotation by pin 48 while the rivet drivers or plungers of the riveter heads are moved downwardly to effect the riveting and then upwardly to clear the lining. When the rivet drivers or plungers have been moved upwardly to their normal or off positions, the clutches are disengaged in a well known manner by cams.

To stop the rotation of the work holder 13 I have provided the stop switch 70 in the circuit to the work-holder motor 58 and the two stop control pins 71 for operating the switch. The stop switch is of standard construction and is adapted to break the electric circuit to the electric motor 58. The stop control pins are mounted on and project laterally beyond the disk 20 and

are positioned to operate the stop switch 70, which is mounted on the frame plate 23, after the lining and brake shoe, which has been fed to the rear of the holder by the rotation thereof, has been completely riveted and before riveting of the lining and brake shoe at the front of the holder begins. More particularly, the stop control pins are diametrically opposite each other between the last of the anvils 27 of one series and the leading anvils 26 of the next series. After the electric circuit to the electric motor 58 has been broken, this circuit cannot again be made until the starter button 72 is manually operated, this starter button as shown being mounted on the floor for foot operation.

To press the lining 17 against the platform 18 of the shoe 16 so that the lining fits tightly against the platform, I have provided the pressure roll 73 which is engageable with the lining in advance of the rivet drivers or plungers. This pressure roll is rotatably mounted on the front end of the lever 74 which is pivotally connected intermediate its ends by the pivot pin 75 to the frame bar 16 of the riveting machine. The rear end of the lever extends between the furcations 77 of the rod 78 and abuts the rounded portion 79 of the rod between the inner ends of the furcations. To hold the rear end of the lever from disengagement, there is the pin 80 extending between the furcations and over the rear end of the lever. The rod 78 is mounted at its lower end in the upper end of the plunger 81 which slidably engages the collar 82 adjustably threaded in the nut 83. The collar is preferably provided at its upper end with transverse holes for engagement by a suitable spanner wrench to effect rotative adjustment of the collar. The nut 83 is clamped to the table 25 by the plate 84 which is bolted to the table. The plunger 81 is formed with the longitudinally extending recess 85 extending upwardly from its lower end into which freely extends the stud 86 threadedly engaging the table 25. 87 is a coil spring within the recess between its upper end and the plate 88 abutting the upper end of the stud. This coil spring yieldably urges the plunger 81 upwardly to yieldably urge the pressure roll 73 downwardly through the lever 74 on which it is mounted. The stud 86 is adjustably mounted in the table to vary the force exerted by the coil spring 87, and to further vary and secure finer adjustment of the pressure exerted by the pressure roll there is the inner coil spring 89 which is weaker than the coil spring 87 and which abuts the upper end of the recess in the plunger 81 and the upper face of the nut 83 threaded on the inner stud 88' adjustably threadedly engaging the stud 86. The inner stud is encircled by the lower end portion of the coil spring 87 so that this inner stud serves to pilot this coil spring. The inner coil spring 89 encircles the rod 90, which slidably engages the upper end portion of the plunger 81 and also the upper end portion of the inner stud 88' and is yieldably urged upwardly by the coil spring 91, the arrangement being such that the rod 90 serves as a pilot for the inner coil spring and is movable downwardly as the plunger 81 is moved downwardly. For limiting the upward movement of the plunger 81, it is formed at its lower end with the annular flange 92 which normally abuts the lower end of the collar 82 and is spaced above the table 25 to provide for downward movement of the plunger 81 as the pressure roll engages the lining.

To laterally position the trailing end of the

lining 17 on the platform 18 of the shoe 16 when the shoe and lining are placed on the holder 13, I have provided the positioning heads 93 (Figs. 5, 6 and 7) having the laterally offset surfaces 93' and 93² for engaging the opposite edges of the platform and lining respectively. These heads have the horizontally extending plungers 94 slidably mounted in the supports 95 at the upper ends of the arms 96 which latter are secured to the base 24 at the front of the machine, the positioning heads extending closely adjacent to the frontmost portions of the peripheries of the disks 19 and 20 of the holder. These positioning heads are urged toward each other by the coil springs 97 abutting the plungers and the supports and are limited in their movement toward each other by the stops 98 secured to the supports. The portions 99 of the outer faces of the positioning heads beyond the lining positioning surfaces and the stops are preferably bevelled to laterally guide the shoes and linings while being inserted in place. With this construction, the positioning heads laterally position the trailing end of the lining with respect to the trailing end of the shoe platform while the pins of the leading anvils position the leading end of the lining with respect to the leading end of the shoe platform when the shoe and lining are first inserted into place. Also, the positioning heads continue to function until the shoe and lining have been sufficiently riveted together to maintain the proper lateral position of the lining on the shoe.

For the purpose of removing the shoe and lining after they have been riveted together, the stripper 100 (Fig. 6) is provided extending into the lower portion of the channel 14 of the holder and engageable with the leading end of the shoe. This stripper is preferably in the nature of a plate resting on the base 24 and secured to the plate 22 by the bolt 101.

Assuming the riveting machine to be at rest with the uppermost control pin 71 slightly to the left of the vertical plane of the rivet drivers or plungers 6 of the riveter heads 1 (the at rest position being the Fig. 6 position turned slightly counterclockwise) and also assuming that a shoe and lining have been mounted on the front portion of the holder 13 and positioned by the pins 29 of one of the pair of leading anvils 26, the operator starts the fly wheels 10 of the riveting machine by depressing a suitable button to make the electric circuits to the riveter motors 12 and then by depressing the work-holder starter button 72 makes the electric circuit to the work-holder motor 58 to set the cam wheel 56 into continuous rotation. Upon rotation of the cam wheel 56 the slide 39 is first moved rearwardly (to the right in Fig. 3) by the cam groove 57 of the cam wheel 56 engaging the roll 55 on the actuator plate 54 which is secured to the slide 39 to thereby pull cam-slide 61 rearwardly to disengage the positioning pin 48 from the lowermost of the holes 38 and hold the positioning pin in inoperative position until the work holder 13 in the forward movement of the slide 39 has been indexed a sufficient distance to position the lowermost hole beyond the positioning pin. The rotative advance of the work holder is effected upon the forward movement of the slide by engagement of the abutment face 46 of the dog 42 with the pin 37 next in rear of the positioning pin 48. At the end of this forward movement of the slide said pin has been advanced to its lowermost position at which time, the cam slide 61 having released the positioning pin 48 during forward

movement of slide 39, the pin 48 engages the next hole and the work holder is held from rotation. Just before the leading anvils 26 come into axial alignment or registration with the rivet drivers 6 or plungers 6 the control pins 66' and 68' engage respectively the pin 69' of the levers 69 of the solenoid controlling time limit switches 66 and 68 and these limit switches make the electric circuits through the solenoids 65 of both riveter heads thereby energizing the solenoids just long enough to trip both clutches 11 to connect the fly wheels 10 to the crankshafts 9. The widths of the abutment pins 69' of the levers 69 of the limit switches controls the length of time that the solenoids are energized, de-energizing taking place substantially simultaneously with the pin 48 engaging the above referred to next hole 38. The crankshafts 9 lower the rivet drivers or plungers 6 to carry the rivets downwardly into the registering holes of the lining and shoe platform, the rivets depressing the guiding pins 29 of the leading anvils. At the lower end of the strokes of the rivet drivers or plungers the lower ends of the shanks of the rivets are headed by the guiding pins 29 and bodies 28 of the leading anvils after which the rivet drivers or plungers are raised to their uppermost positions and the clutches 11 are automatically thrown out or moved to disengaged position by their spring controlled cams, the crankshafts having made one revolution. It will be noted that during the riveting operation, the positioning pin 48 remains in engagement with the lowermost hole 38 although the slide 39 is being moved rearwardly, this being effected by the distance the positioning pin extends into the hole and also by the dwell of the cam 61 in advance of the cam faces 64.

The steps of indexing the holder and riveting the lining to the shoe platform continue to be carried out during which the control pins 66², 68² and 68³ successively operate their respective limit switches after which the last control pins 66³ and 68⁴ of their series simultaneously operate their respective limit switches completing the riveting of the lining to the shoe. During these riveting steps the pressure roll 73 holds the lining against the shoe platform, the pressure roll engaging the leading end of the lining as it and the shoe are advanced after the first riveting step. After the riveting of the lining and shoe has been completed the holder is indexed one rotative step, without operation of the rivet setter mechanism, to advance the trailing end of the riveted lining and shoe so that it will not interfere with the insertion or mounting on the front portion of the holder of another unriveted shoe and lining. Upon completion of this last rotative step of holder 13 the succeeding pin 71 operates the stop switch 70 to break the electric circuit to the motor 58 and the intermittent rotation of the holder 13 stops. After the unriveted shoe and lining have been positioned on the holder the starter button 72 is again depressed to start the motor 58 to again effect intermittent rotation of the holder 13, during which the holder is first indexed one intermediate rotative step and then another rotative step before the pins 66' and 68' engage the abutment pins 69' of the levers 69 of their respective limit switches 66 and 68. During the intermittent rotation, the newly added lining is riveted to the shoe platform and during the first portion of this riveting operation the previously riveted lining and shoe are stripped from the holder by the stripper 100.

What I claim as my invention is:

1. A machine for riveting arcuate work elements having registering substantially radial holes arranged in a plurality of series spaced laterally of the work elements comprising a rotatable holder for peripherally receiving the work elements, a plurality of series of substantially radially extending anvils on said holder for registering with the holes, a separate riveter head for each series of holes having a rivet driver movable toward and away from said holder substantially radially thereof, separate means for moving said drivers, means for rotating said holder step by step to positions successively registering said anvils with said drivers, separate means for controlling the operation of each of said driver moving means each having a limit switch, and means on said holder for operating each of said limit switches, said last mentioned means being positioned to operate the limit switches controlling the operation of the moving means for the drivers when the drivers are in registration with an anvil.

2. A machine for riveting arcuate work elements having registering substantially radial holes arranged in a plurality of series spaced laterally of the work elements comprising a rotatable holder for peripherally receiving the work elements, a plurality of series of substantially radially extending anvils on said holder for registering with the holes; a separate riveter head for each series of holes having a rivet driver movable toward and away from said holder substantially radially thereof, separate means for independently moving each of said drivers, separate means for controlling each of said driver moving means, means for rotating said holder step by step to positions registering said anvils with said drivers, and separate means including a different series of members carried by said holder for each controlling means for independently initiating operation of said controlling means.

3. A machine for riveting work elements having registering holes arranged in a plurality of series spaced laterally of the work elements comprising a rotatable holder for the work elements, a plurality of series of anvils on said holder for registering with the holes, a separate riveter head for each series of holes having a rivet driver movable toward and away from said holder, means for moving said drivers, means for rotating said holder step by step to positions registering said anvils with said drivers, and means for controlling the operation of one of said driver moving means independently of another, said means comprising clutches, means for operating said clutches, means for controlling the operation of said operating means and means movable in unison with said holder for operating said controlling means.

4. A machine for riveting a brake shoe having an arcuate platform and a lining, the platform and lining having registering substantially radial holes arranged in a plurality of rows spaced laterally of the platform and lining comprising a rotatable holder for the shoe and lining, a plurality of rows of anvils on said holder for registering with the holes, a separate riveter head for each row of holes having a rivet driver movable toward and away from said holder, separate means for independently moving each of said drivers, means for rotating said holder step by step to positions registering said anvils with said drivers, means for controlling the operation of one of said driver moving means independently of another, and

means on said holder for initiating operation of said controlling means.

5. A riveting machine comprising a rotatable work holder, circumferentially spaced anvils on the periphery of said holder, a rivet driver reciprocable toward and away from said holder substantially radially thereof, means for reciprocating said driver, normally rotating members, reciprocable means operable by one of said members for advancing said holder step by step to positions registering successive anvils with said driver, and means for controlling the operation of said driver reciprocating means by the other of said members, and means on said holder for initiating operation of said controlling means.

6. A riveting machine comprising a work holder rotatable about a horizontal axis, circumferentially spaced anvils on the periphery of said holder, a rivet driver reciprocable toward and away from said holder substantially radially thereof, a crank shaft for reciprocating said driver, normally rotating members, reciprocable means operable by one of said members for advancing said holder step by step to positions registering successive anvils with said driver, a clutch for coupling said crank shaft to the other of said members, means for controlling the operation of said clutch and means on said holder for initiating operation of said controlling means.

7. In a machine for riveting a brake shoe and lining having registering holes arranged in series, a rotatable holder for peripherally receiving the brake shoe, series of circumferentially spaced peripheral anvils on the periphery of said holder for registering with the holes, one of said anvils being provided with a movable pin engageable in the registering holes in the leading ends of the shoe and lining to position the leading ends of the shoe and lining on said holder and with respect to each other, and laterally movable abutments adjacent said holder and engageable with the opposite edges of the trailing end of the lining to laterally position the same with respect to the trailing end of the shoe, said abutments having bevelled faces diverging with respect to each other away from the periphery of said holder.

8. In a machine for riveting a webbed brake shoe and lining, a rotatable holder for peripherally receiving the brake shoe and having a radially extending channel for receiving a web of the brake shoe, series of circumferentially spaced peripheral anvils on the periphery of said holder at opposite sides of the channel, one of said anvils being provided with a movable pin engageable with the leading end portions of the shoe and lining to circumferentially position the shoe and lining on said holder and laterally position the leading end portion of the lining relative to the leading end portion of the shoe, and spring pressed laterally movable abutments for engaging the edges of the trailing end portions of the shoe and lining to laterally position the trailing end portion of the lining with respect to the trailing end portion of the shoe, said abutments having bevelled faces diverging with respect to each other away from the periphery of said holder.

9. In a machine for riveting a pair of work elements, a holder for the work elements rotatable about its axis and having concentric series of holes and pins, a slide reciprocable chord-wise of said holder, a dog movably mounted on said slide and successively engageable with said pins to index said holder on movement of said slide in one direction, a positioning member movable axially of

11

said holder for successively engaging the holes at the end of the movement of said slide in one direction and means movable with said slide in the opposite direction to disengage said positioning member from the hole engaged thereby.

10. In a machine for riveting a pair of work elements, a holder for peripherally receiving the work elements and having concentric series of holes and pins arranged in pairs, a slide reciprocable chord-wise of said holder, a pivotal dog on said slide successively engageable with said pins to index said holder on movement of said slide in one direction, a positioning pin movable axially of said holder for successively engaging the holes at the end of the movement of said slide in one direction and cam means movable with said slide in the opposite direction to disengage said positioning pin from the hole engaged thereby.

11. In a machine for riveting a pair of work elements, a holder for the work elements rotatable about its axis, circumferentially spaced peripheral

15

5 anvils on said holder, rivet driver means movable toward and away from said anvils, a pressure roll engageable with one of the work elements in advance of said rivet driver means to press the same against the other of said work elements, an adjustable abutment member, a spring abutting said member for yieldably urging said pressure roll toward the first mentioned work element, a second abutment member threadedly engaging said first mentioned abutment member and a spring abutting said second abutment member for also urging said pressure roll toward the first mentioned work element.

12 FRANK H. LE JEUNE.
